UNITED STATES PATENT OFFICE.

PAUL WARRINGTON EVANS, OF WASHINGTON, DISTRICT OF COLUMBIA.

DENTAL BRACKET-TABLE.

No. 893,155.

Specification of Letters Patent.

Patented July 14, 1908.

Application filed November 1, 1907. Serial No. 400,205.

To all whom it may concern:

Be it known that I, PAUL WARRINGTON EVANS, of Washington, in the District of Columbia, have invented certain new and useful Improvements in Dental Bracket-Tables; and I do hereby declare the following to be a full, clear, and exact description of the invention, such as will enable others skilled in the art to which it appertains to make and use the same.

My invention relates to improvements in bracket tables for use of dentists,—the object of the invention being to so construct such a table that it can be made to contain the operating tools and accessories used by a dentist, and in which they can be so arranged as to be readily accessible with the use of one hand of the operator while the other hand is engaged with the patient.

20 A further object is to so construct a bracket table that the various instruments and accessories used by a dentist can be systematically arranged and their cleanliness insured, and confusion as well as accumulation 25 of instruments upon the table top avoided.

A further object is to so construct the device that a place will be provided for every instrument and accessory used by a dentist while treating a patient.

30 With these objects in view the invention consists in certain novel features of construction and combinations and arrangements of parts as hereinafter set forth and pointed out in the claims.

35 In the accompanying drawings, Figure 1 is a perspective view of a dentist's bracket table embodying my improvements. Fig. 2 is a plan view. Figs. 3 and 4 are sectional views taken at right angles to each other.

40 Fig. 5 is a view of one side of the device. Fig. 6 is a view of another side of the table, and Fig. 7 is a detail view illustrating one of the latch devices for holding the rods 17 and bars 16 elevated.

45 1 represents the main or body portion of the table, which may be constructed of any suitable material and divided into a series of compartments as hereinafter explained.

This main or body portion 1 of the device is 50 secured upon a base bracket 2, the central portion of which is provided with a depending, tubular shank or stem 3 which passes through a suitable bracket arm 4, upon which the base bracket 2 is revolvably supported, whereby the table can be readily

turned by the operator as occasion may require. To the lower end of the tubular shank 3 a gas supply pipe 5 is connected by means of a suitable coupling 5^a and the tubular shank 3 communicates with a duct 6 in 60 the central portion of the base bracket 2. With this duct one end of a pipe 7 communicates, said pipe extending to one corner of the table and then upwardly through the table and provided at a point above the latter with a burner 8 and a bracket 9 for the accommodation of an annealing tray or pan. An auxiliary adjustable burner 10 is also preferably provided and disposed over the table within convenient reach of the operator. 70

The table top consists of a slab 11 which may be made of enameled wood or steel, or of plate or porcelain glass, and is removably held in place by means of bars 12 and the latter are secured in position by means of 75 thumb-nuts 13 screwed upon the upper ends of rods 14 which pass through said bars and the corners of the structure. Racks 15 are located upon the slab or table top 11 and are removably held in place by means of the 80 bars 12. These racks having notches for the reception of dental tools upon the table for preventing such tools from rolling. From this construction it will be seen that the slab 11 as well as the racks 15, can be 85 readily removed when it is desired to clean or sterilize them or when it is desired to place a different top upon the table.

The bars 12 are provided with removable sections 16, each of which is attached at its 90 respective ends to rods 17 which pass downwardly through suitable guide tubes 18 located within the table structure. The bar sections 16 can be raised to the position shown in Figs. 1, 5 and 6 and held in place 95 by means of spring actuated latches 19 which engage notches 20 in the rods 17 as shown in Figs. 1 and 7. An elevated support is thus formed for the reception of a tray 21 which comprises a rectangular frame 22 and a bottom 23 of wire gauze. This tray is for the reception of tools or other devices for which the dentist may have immediate need and portions of the frame 22 are notched as shown at 24, Fig 6, to receive the handles of 100 tools for preventing the latter from rolling. By making this tray with a wire gauze or open-work bottom, light may pass through it to the table top or slab 11.

The body portion 1 of the table is divided 110

into a series of compartments 25, 26, 27, and 28, by means of partitions suitably disposed, as best shown in Fig. 2. The compartments 25 and 26 will be normally closed by means of a door 29 hinged at the lower edge of the structure and provided with slotted arms 30 which move over pins 31. The door 29 may thus be disposed (when open) in a horizontal position and serve to support trays or instrument racks 32, 33 when the latter are partially removed from the compartments 25—26 in which they are normally inclosed. The rack 32 comprises a frame which may be conveniently made of sheet metal and a series of trays 34 having wire netting bottoms arranged in step formation. The front edge of each tray 34 is provided with a series of notches 35 to prevent tools placed upon said trays from rolling. By making the trays 34 with wire gauze bottoms, all dust accumulation will be permitted to pass to the bottom of the structure 32. This rack or structure 32 is bodily removable from the table and can therefore be cleaned and sterilized whenever necessary. The tray 33 is adapted for the reception of small articles which the dentist may use in his practice and this tray is also bodily removable from the table and may be supported in a partially withdrawn position, by the door 29 in the same manner as the rack 32 is shown supported in Fig. 1. The compartment 27 at the opposite side of the table contains a series of drawers 36 and in the compartment 28 a rack 37 is located and normally inclosed therein by means of a hinged door 38. The rack 37 comprises side supports 40, pivoted cross members 41 and ledges 42 upon which trays 43 are supported. Stops 44 are provided so that when the lower portion of the rack is pulled outwardly the trays 43 will become disposed in step formation to give ready access to the small instruments which may be disposed upon said trays. These trays are removable and can therefore be thoroughly cleansed from time to time.

Projecting from two corners of the body 1 of the device are receptacles 45 and 46. The receptacle 45 is made with compartments 47 and 48 for the reception of absorbent cotton rolls, and upon said receptacle 45, a slab 49 is located to permit the mixing of cement or amalgam. This slab is preferably removable as is also a slab 50 located upon the receptacle 46 and these slabs may be used interchangeably upon the receptacles 45 and 46. The slab 50 is made with a depression 51 for holding water for grinding purposes. The receptacle 46 contains a step holder 52 for the reception of dental grinding devices and polishing brushes. The receptacle 46 is normally closed by a door 53 and to this door a step holder 54, similar in construction and for the same purpose as the holder 52,

is secured. To the bottom of the receptacle 45 a spring clip 55 is located for holding glass floss silk holder.

Between the receptacles 45 and 46 a compartment 56 is located and the front of this compartment is normally closed by means of a door 57 while its top may be closed by means of a slide 58 mounted in guide-ways 59 under the table top, the ends of said slide being also supported when the slide is pulled outwardly to cover the compartment 56, by the upper edges of the receptacles 45 and 46. Within the compartment 56 a rack 59 for test tubes is located and in the bottom of this compartment a tray 60 is disposed. Within the compartment 56 and over the shallow tray 60 holders 61 for burs, plugger points, reamers and the like are disposed. These holders comprise blocks or strips having sockets adaptable for the reception of the tools above mentioned and these blocks or strips are removably held by means of socketed, pivotally supported blocks 62. With this construction the holders 61 can be tilted so as to dispose the tools in an inclined position in which the operator can most readily examine them to select the particular tool he desires to use. The door 57 of the compartment 56 is provided with several series of bur holders 63, one series disposed over the other and each holder adaptable for the reception of several burs.

At the corners of the table opposite the receptacles 45 and 46 are other receptacles 64, 65. The door 66 of the receptacle 64 is preferably so hinged as to be movable in a horizontal plane and carries a holder 67 similar in connection to the holders 52—54 of the receptacle 46. The receptacle 65 is provided on its top with a mixing slab 68 and to the bottom of this receptacle a hook 69 is secured and projects laterally therefrom, said hook being preferably so mounted that it can be pulled outwardly and serve to receive the arm of a dental engine and hold the same when not in use. This hook may also be utilized to temporarily hold a syringe. The receptacle 65 is provided with a compartment 70 for the reception of cotton balls or pellets and this compartment is made with a lateral opening. The receptacle 65 is also provided with a compartment 71 for the reception of loose absorbent cotton and the side wall of this compartment is provided with a series of slots 72 through which particles of cotton can be withdrawn by the means of pliers. A box 73 is hinged at its lower edge to the lower edge of the receptacle 65 and the top of this box is open for the reception of waste. One side or end of the box 73 is made with an irregularly shaped opening 74 to facilitate the insertion of waste and its removal from a dental tool.

Between the receptacles 64 and 65 is a compartment 75, the top of which is nor-

mally closed by means of a slide 76, similar in all respects in its construction and mounting to the slide 58 hereinbefore described. A tray 77 is located in the bottom of the compartment 75 and this tray is sub-divided for the accommodation of mixing slabs 78, a sharpening stone 79, and for the reception of filling material.

Located within the compartment 75 is a series of spring supports 79, so disposed as to hold a horizontal series of removable wide-mouthed bottles or jars 80 in an inclined position as most clearly shown in Fig. 4 and also as shown in Fig. 5. The cover 81 of each bottle or jar is provided with a cushion 82 to engage the mouth of the bottle or jar and said cover is pivotally connected to an arm 83. Each arm 83 is pivotally supported by lugs 84 and provided with a cam projection 85 engaged by a spring 86. With this construction, it will be seen that the operator can, with the use of one finger raise a cover from a bottle or jar by manipulating the arm 83 and that he can again close the bottle or jar by pressing downwardly on said arm. By pivotally connecting the covers 81 to the arms 83, said covers will adapt themselves to the bottles or jars even though the latter may be slightly misplaced within the holders. The compartment 75 will be normally closed by means of a hinged door 87.

One or more handles 88 may be provided whereby the operator can readily rotate the table.

With the use of my improvements the dentist will have all of his instruments and accessories systematically arranged and within convenient reach so that he can take them with one hand while the other hand is engaged with the patient. It is also apparent that the various holding means provided can be kept clean and sterilized.

Having fully described my invention what I claim as new and desire to secure by Letters-45 Patent, is,—

1. A dental bracket table provided with a series of bottle or jar supports at one side, a series of bottles or jars mounted in said supports, a series of pivoted arms over said bottles or jars, covers for said bottles or jars pivotally connected to said arms and provided on their under faces with cushions a spring for each cover, and means cooperating with said springs and pivoted arms to retain the covers in either a closed or an open or raised position.

2. A dental bracket table provided at two corners with outwardly projecting receptacles forming a compartment between them, a slide constituting a movable cover for said compartment, holders for dental appliances within said compartment and a door co-operating with said slide for closing the said compartment.

3. A dental bracket table constructed at one side of its body portion with a compartment, a tilting instrument holder mounted within said compartment and means for closing the compartment.

4. A dental bracket table provided at one side of its body portion with a receptacle or compartment, tilting blocks mounted in said compartment, instrument holders removably mounted in said tilting blocks, and means for closing said compartment. 75

5. A dental bracket table provided at one side of its body portion with a compartment to receive dental appliances, a slide constituting a movable cover for said compartment, a door co-operating with said slide to close the compartment, and superimposed series of bur holders on the inner side of said door.

6. A dental bracket table provided at one side of its body portion with two receptacles, one of said receptacles having compartments 85 to receive cotton and the other receptacle provided with instrument holders, a slide for covering the compartment between said receptacles, and a door co-operating with said slide to close said compartment between the 90 receptacles.

7. A dental bracket table provided with receptacles at its corners and with slabs mounted upon said receptacles, two of said receptacles divided into compartments to 95 receive cotton in various forms and the other receptacles provided with instrument holders.

8. A dental bracket table provided at one side of its body portion with a receptacle having compartments for cotton, one of said 100 compartments having one or more contracted outlets, and a waste box hinged to said receptacle and provided in one wall with an irregularly shaped opening.

9. A dental bracket table provided with a removable top slab, bars for holding said slab in position, said bars provided with movable sections, rods secured to said sections and movable through said bars, said bar sections when elevated constituting means for supporting a tray over the table top, and spring pressed latches engaging said rods to retain the bar sections in elevated position. 110

10. A dental bracket table provided with a removable slab or top, bars secured to the 115 table for holding said slab or top in position, and tool racks located upon and removable from the table top or slab, said tool racks normally held in place by said bars.

11. A dental bracket table divided into a 120 series of compartments, two of said compartments opening at one side of the table and the other two compartments opening at the other side of the table, tool holding means removably disposed within two of said compartments, a single door for closing said last-mentioned compartment and means for holding said door in a horizontal position when 125

open to serve as a support for said tool holding means when the latter shall have been partially withdrawn.

12. A dental bracket table divided into a series of compartments, an adjustable rack located within one of said compartments and provided with a series of superimposed trays, a door for closing this compartment, a series of drawers occupying another of said compartments, and a series of superimposed tool holding trays having open work bottoms disposed within and bodily removable from another of said compartments.

13. A dental bracket table provided with a series of compartments to receive dental tool holding means, receptacles projecting from the body portion of the table, a clip depending from one of said receptacles, a hook attached to another of said receptacles and means for inclosing dental appliances between the pairs of receptacles at opposite sides of the body portion of the table.

14. The combination with a bracket, of a dental table revolvably mounted thereon and provided with a gas inlet, a gas pipe communicating with said inlet, and a burner connected with said pipe and adjustable over the table. 25

15. The combination with a bracket, of a dental table revolvably mounted upon said bracket, and having a tubular shank passing through the bracket, a coupling for connecting a gas supply pipe with the tubular shank of the revolvable table, a gas pipe communicating with said tubular shank and extending to the top of the table, and a burner at the upper end of said last-mentioned pipe. 30 35

In testimony whereof, I have signed this specification in the presence of two subscribing witnesses.

PAUL WARRINGTON EVANS.
